UNITED STATES PATENT OFFICE

LEOPOLD SPIRA, OF ZURICH, SWITZERLAND

PAINT PULVERIZER

Application filed July 22, 1929, Serial No. 380,096, and in Switzerland July 23, 1928.

The subject of the present invention is a paint pulverizer with pressure agent nozzle and suction nozzle arranged before the latter. Devices of this kind hitherto known have the drawback that the nozzles either cannot be displaced at all or can only be displaced in one direction relatively to each other, so that either only the form of the jet of paint, or only the quantity of paint contained in the jet can be altered, but not both at the same time.

This defect has been avoided in the paint pulverizer according to the present invention by the fact that means are provided making it possible to displace the nozzles, which are at a right angle to each other, in the direction of the nozzle axes, owing to which displacement the form of the jet of paint and the quantity of paint contained therein, can be modified.

Moreover each of the nozzles can be regulated individually.

On the drawings annexed different constructional examples of the subject of the invention are shown in which:

Fig. 1 is a section of the first form of embodiment,

Fig. 2 a view in section of a second form of execution,

Fig. 3 a view of detail,

Fig. 4 a section of another modified form of the invention, and

Fig. 5 a plan view of the same.

The paint pulverizer, shown in Figs. 1, 2 and 3, has a paint container 1 from which the paint is fed through a conduit 2 to the paint nozzle 3. At the bottom end of this feed conduit 2, a filter 4 is fitted, being fixed by means of a bayonet joint 5. The object of the filter 4 is to prevent the choking up by thickened paint of the nozzle 3, which has always taken place hitherto, and this does away with the troublesome and frequently recurring cleaning of the nozzle.

On the paint container 1 a plate 6 is fixed from which a part 7 is punched out and bent away at a right angle, so that it can serve as the guide for a part of the pressure agent supply conduit. The plate 6 serves to carry a handle 8 which is fastened by means of a

lock nut 9, to the plate 6. The handle 8 embraces the lower part of a valve casing 10, with the valve body 11. Integral with the valve casing 10 there is the pressure agent feed conduit 12, the lower part of which is provided with inside screw thread. In the part fitted with screw thread, there engages a further feed conduit part having an external thread. With a part 13, there is connected a grooved piece 14 having a milled edge 16. In the groove of the piece 14 and a corresponding groove of the handle 8 a ring 15 engages which serves to hold the parts 13, 14, 16. A ring 17 fixed by a screw 18 acts as a guide ring for the feed duct part 12.

The rod 19 which carries at one end the valve body 11, and which is guided in the valve case 10, is connected at its other end with a knob 20 which is under the action of a spring 21, which causes the knob 20 to move upwards, and thus to press the valve body 11 on its seat. The knob 20 has a depending flange 22, which is prolonged at one point into a part 23 bent at a right angle. The horizontal arm of the part 23 can be brought into engagement by turning the knob 20, with a pin 24, fitted on the valve case 10, to hold the valve 10 in open position. In the upper part of the valve case 10 the pressure agency conduit part 25 branches off at a right angle to its axis and is connected with a part 26 having an external screw thread. Over this part 26, an internally threaded sleeve 27 which is fixedly connected with the feed duct part 28, carrying the nozzle 29, is slidable. The sleeve 27 can be locked tight by means of a locknut 30.

By rotating the disc 16, the feed conduit part 12 and with it the valve case 10, and the nozzle 29 are shifted along the axis of the paint nozzle. This vertical displacement effects an alteration of the quantity of paint discharged from the paint nozzle when operating the paint pulverizer. By turning the sleeve 27, the nozzle 29 is shifted axially, and this horizontal displacement produces an alteration of form of the jet of paint emerging.

The relative displacement of the two nozzles, the one to the other, is produced by the

regulating of only one nozzle, i. e. the nozzle 29.

The rotation of the sleeve 27 can be carried out by the hand by which the handle 8 is held, so that the other hand remains free. The rotation of the disc 16, which effects the vertical displacement of the nozzle 29 can be carried out with the left hand while the right hand grasps the handle.

10 For regulating the nozzle 29 in vertical direction, the feed conduit part 12 could also be provided at its lower end with external thread entering into the internal thread of the piece 14, the latter surrounding the under end of 15 conduit 12 and thus replaces the guiding ring with the screws 18.

The arrangement described of the two means for shifting the nozzles renders the paint pulverizer very practical in actual handling, because the operation of the said means is very simple. The possibility of fixing the valve in the open position entails the advantage that it is not necessary continuously to press down the knob, but the whole hand is 25 left free for handling the pulverizer.

In the form of the invention shown in Fig. 2 the valve case 10 is arranged in a tubular sleeve 31 which is threaded in the upper end of the member 8.

30 The paint pulverizer according to Figs. 4 and 5 comprises again a paint container 1, wherefrom the paint is conducted to the paint nozzle 3 by means of the conduit 2. To the cover of the container 1 is fixed a plate 6 which 35 serves to support the handle 8 forming a part of the pressure agent feed conduit. The handle 8 is attached by means of a part 9, acting like a counter pressure screw, to the plate 6, this part 9 serving at the same time as a 40 valve body.

On the plate 6 is fixed by means of a screw 34 an oscillating lever 35, the extremity whereof, directed towards the nozzle 3, is provided with a teeth segment 36. The latter engages a similar part 37 provided on the circumference of the body of the paint nozzle. The under end of the nozzle body has a thread 38 which engages into the interior thread of 50 the paint feeding conduit 2, so that by oscillating the lever 35, the paint nozzle 3 is turned around its axis by means of the toothed segment 36 and the teeth 37; it therefore is moved to and fro in the direction of its axis and approaches or becomes distant from the nozzle 29.

Through an opening 39 of the lever 35 emerges a part 7 serving as a guide for the nozzle 29, the said part 7 acting at the same 60 time like an abutment for the oscillating movement of the lever 35. On the opposed extremity the plate 6 shows an index pointer 40 which allows in cooperation with the scale 41 to control the movement of the lever 35.

65 The regulating of the nozzle 29 is operated

in the above described manner, i. e. by means of the threaded parts 26, 27.

The rod 19 guided within the upper part 9 has a valve body 11 and a knob 20 which is pressed upwards by a spring 21, so that the valve body 11 is continuously closed. The rod 19 is provided with a pin 42 which can be displaced within the slot 43 of the body 9. At the under end of the slot 43 is provided a shoulder 44, against which the pin 42 abuts when the knob 20 and the rod 19 together with the said pin is pressed down and turned around its axis. In this position the valve body remains lifted and the valve is open.

At the under end of the handle 8 there is 80 provided on the conduit 45 a nut 46 serving for the straight connection with a flexible pipe etc. 47.

The described arrangement of the means for regulating both the nozzles and the means 85 for actuating the valve have the advantage that all the three means can be operated by the fingers of that hand which grasps the handle 8. The other hand remains thus free and can operate the pumps which furnish for 90 instance the pressure agent.

I claim:

Apparatus of the class described, including a suction nozzle for the discharge of paint and the like, and a nozzle for the discharge of 95 fluid under pressure, said nozzles being arranged substantially at right angles to each other and each with its discharge end spaced from the discharge end of the other, the second named nozzle being movable axially 100 and being also movable laterally with respect to the paint discharge nozzle.

In testimony whereof I have hereunto set my hand this 8th day of July A. D. 1929.
